CLAIM

(21) Appl. No.: **29/516,180**

The ornamental design for an enclosure for multi-frequency band signal booster system, as shown and described.

(22) Filed: **Jan. 29, 2015**

DESCRIPTION

(51) **LOC (10) Cl.** **13-03**

FIG. 1 is a front elevational view of an enclosure for multi-frequency band signal booster system, showing the new design;

(52) **U.S. Cl.**

FIG. 2 is a top plan view of the enclosure of FIG. 1;
FIG. 3 is a bottom plan view of the enclosure of FIG. 1;
FIG. 4 is a left elevational view of the enclosure of FIG. 1;
FIG. 5 is a right elevational view of the enclosure of FIG. 1;
FIG. 6 is a rear elevational view of the enclosure of FIG. 1;
and,

(58) **Field of Classification Search**

FIG. 7 is a top-left perspective view of the enclosure of FIG. 1.

USPC ..... D13/184; D14/230-238; 343/700 R,

343/872, 873

CPC H01Q 1/42

See application file for complete search history.

The broken lines illustrate portions of the enclosure for multi-frequency band signal booster system which form no part of the claimed design.
